UNITED STATES PATENT OFFICE.

MICHAEL DALY, OF CINCINNATI, OHIO, ASSIGNOR TO AMERICAN LAUNDRY MACHINERY CO., OF CINCINNATI, OHIO, A CORPORATION OF OHIO.

EXTRACTOR-COVER.

1,217,418.

Specification of Letters Patent. Patented Feb. 27, 1917.

Application filed November 24, 1914. Serial No. 873,817.

To all whom it may concern:

Be it known that I, MICHAEL DALY, of Cincinnati, in the county of Hamilton and State of Ohio, have invented certain new 5 and useful Improvements in Extractor-Covers; and I do hereby declare the following to be a full, clear, and exact description of the same, reference being had to the accompanying drawings, forming a part of 10 this specification, and to the reference numerals marked thereon.

My invention has for its object to provide a cover that is applicable to casings or receptacles, and relates more particularly to 15 the type of cover employed for extracting machines, which are used in connection with laundry apparatus for removing moisture from wet clothing. One of the purposes of the invention is to provide a cover that can 20 be manufactured at a reasonable cost, and is of minimum weight so as to facilitate operating the machine when it is necessary to open and close the cover. A further object of my improvement is to afford a construction that is rigid, strong and durable, 25 and which will permit the operator to view the interior of the machine through the cover when the latter is closed. To these and other ends the invention consists in cer- 30 tain improvements and combinations of parts, all as will be hereinafter more fully explained, the novel features being pointed out in the claim at the end of the specification.

35 In the drawings:

Figure 1 is a side elevation, showing the application of my improvement to an extractor;

Fig. 2 is a plan view of the same;

40 Fig. 3 is an enlarged plan view of the cover detached from the casing;

Fig. 4 is a bottom plan view of the same, and

45 Fig. 5 is a sectional view on the line 5^a—5^a of Fig. 3.

Similar reference characters in the several figures indicate the same parts.

Various attempts have been made heretofore to devise a construction for this pur- 50 pose but without much success, owing to the fact that it has been found difficult to provide a cover with transparent portions, through which to afford a view of the interior of the machine, and at the same time retain the strength and rigidity that is

necessarily required in order to withstand the constant usage and hard blows to which the device may be subjected. These objections have been overcome in the present construction by constructing the cover with an 60 open portion over which is laid a transparent sheet of suitable material, the latter being held on the body portion and protec- 65 tively braced by means of a rigid plate having openings through which the transpar- 65 ency may be viewed.

The cover is preferably constructed of sheet metal, and in the present embodiment comprises a circular body portion which includes a rim A that may be provided with 70 a series of openings a. Adjacent to the rim A the cover is formed into a raised or convex portion B, and terminates in a flange C, which is preferably continuous, the flange B extending in a direction parallel to the outer 75 edge of the body portion. Figs. 1 and 2 show the cover in its operative relation to an extractor, D and D' designating the sections of a hinge which are attached respectively to the housing or casing D² and to the cover, 80 the body portion of the cover carrying a handle D³ by which it can be opened and closed.

E designates a flexible sheet or disk of 85 suitable transparent material, such as mica, which is coextensive with and rests upon the flange C. Arranged adjacent to the transparent disk E is a metallic or other rigid plate or disk F, which overlies the disk E and serves to protect and brace the latter. 90 The disks E and F are held in place by attaching means, preferably in the form of rivets extending through the flange C, as shown in Figs. 3 and 4. In order to afford a view of the interior of the receptacle or 95 casing, the rigid plate F is provided with one or more openings G arranged between the center and edge of the plate, but leaving substantial portions at the center and edge intact, so that it can be readily at- 100 tached to the flexible transparent disk. The disks are also secured together at the center, as by means of a rivet e, suitable washers e' being preferably disposed between the disks and the rivet heads.

105 The construction affords a transparent portion for the cover, which transparent portion is constructed in such a manner as to afford a surface that is as strong and rigid as though constructed from an integral solid 110

piece of metal. The entire structure is light, affording a simple and durable combination, the parts of which can be readily assembled and united so as to accomplish all the purposes contemplated by a cover of this character.

I claim as my invention:

A cover including a circular body portion terminating in an inwardly directed flange, 10 a transparent disk of flexible material supported on said flange, a rigid disk located adjacent the transparent disk, securing

means passing through the disks and flange and holding said parts together, and centrally arranged means holding the two disks 15 together, the rigid disk having a plurality of openings therein located between its center and its periphery and exposing the transparent disk.

MICHAEL DALY.
